SPINNING TOY

William Luther Gandy, Remerton, Ga., assignor
of one-half to William A. Greene, Remerton,
Ga.

Application February 12, 1945, Serial No. 577,534

3 Claims. (Cl. 46—72)

This invention relates to spinning toys and more particularly to that class of toys known as tops.

The object of the invention is to supply a form of amusement which is simple in operation and capable of satisfactory manipulation by children.

The invention embodies among its features a holder having a handle through which a plunger operates in such a manner that when the plunger is wholly retracted the top will be released and allowed to drop off the holder spinning.

In the drawings:

Figure 1 is a fragmentary top plan view of a holder showing in dotted lines the top in position thereon ready for release spinning.

Figure 2 is a longitudinal sectional view through the device shown in Figure 1.

Figure 3 is a transverse sectional view taken on the line 3—3 of Figure 1.

Figure 4 is a sectional view taken on the line 4—4 of Figure 3.

Figure 5 is a view similar to Figure 4 showing the plunger in top retaining position, and

Figure 6 is a fragmentary top plan view of the top showing its driving gear in section.

Referring to the drawings in detail the device comprises a holder designated generally 10 and a top designated generally 11.

The holder 10 comprises a handle 12 having attached to one end by means of a ferrule 13 a substantially disk-shaped shield 14. Extending longitudinally from the handle and riveted or otherwise attached to the shield 14 is a reinforcing and supporting strip 15 carrying at a point at the center of the shield a centering pin 16 upon which the top 11 is adapted to be rotatably supported as will be more fully hereinafter described. The shield 14 as shown in Figures 2, 4 and 5 is provided with reinforcing flanges 17 which also serve to prevent the hand of the user from interfering with the rotation of the top about the centering pin 16 while it is on the aforesaid pin.

The handle 12 is provided with a longitudinal bore 18 in which a plunger 19 is slidably mounted and secured to the plunger 19 at the end of the handle 12 opposite the shield 14 in an operating knob 20 the use of which will more fully herein-after appear. Formed on the end of the plunger at the end opposite the knob 20 is an offset extension 21 carrying along one edge a plurality of rack teeth 22 for engagement with a pinion carried by the top 11 as will be more fully herein-after described.

The top 11 comprises a substantially conical body 23 carrying at its smaller end a spinning

point 24 and at its larger end in axial alignment with the point 24 a driving device designated generally 25. This driving device comprises a substantially tubular body 26 carrying intermediate its ends an annular outstanding attaching flange 27 which is pierced at spaced intervals for the reception of attaching members such as nails or tacks 28 by means of which the driving device is attached to the top body 23 and parts held against relative rotation. As shown one end of the tubular body 26 is received in a recess 29 formed in the body 23 while the opposite of the tubular body projects beyond the top body and carries at its outer end a retaining flange 30. Formed on the tubular body between the flanges 27 and 30 is an annular series of teeth 31 arranged to mesh with the rack teeth 22 when the top 11 is in place on the holder 10.

In use the knob 20 is moved into the position 20 shown in Figures 2 and 4 so as to completely retract the plunger 19 and move the offset extension 21 into a position to freely allow passage of the flange 30 as the top is mounted in place on the centering pin 16. The top being placed on the holder with the centering pin 16 entering the tubular body 26, the knob 20 is moved to the position shown in Figure 5 thus causing the rack teeth 22 to engage the teeth 31. The top 11 thus is held in position on the holder 10 by the engagement of the flange 30 with the offset extension 21 until such time as the knob 20 is again returned to the position shown in Figures 2 and 4. By quickly retracting the knob the top 11 will be set in rapid rotation and when the end of the offset extension 21 moves clear of the flange 30 the top will be discharged from the holder spinning.

While in the foregoing there has been shown and described the preferred embodiment of this invention it is to be understood that minor changes in the details of construction, combination and arrangement of parts may be resorted to without departing from the spirit and scope of the invention as claimed.

What is claimed is:

1. In a spinning toy in combination, a holder comprising a handle, a reinforcing and supporting strip extending longitudinally from one end of the handle, a longitudinally movable rack mounted in the handle and lying adjacent the reinforcing and supporting strip, a centering pin carried by the supporting strip to one side of the rack, a spinning top body having a spinning point at one end, a driving device at the opposite end of the top in axial alignment with the point, and

means on the driving device cooperating with the rack for rotating the top and holding it on the centering pin during longitudinal movement of the rack.

2. In a spinning toy in combination, a holder comprising a handle, a reinforcing and supporting strip extending longitudinally from one end of the handle, a longitudinally movable rack mounted in the handle and lying adjacent the reinforcing and supporting strip, a centering pin carried by the supporting strip to one side of the rack, a spinning top body having a spinning point at one end, a driving device at the opposite end of the top in axial alignment with the point, gear teeth on the driving device for meshing engagement with the rack during its longitudinal movement and a retaining flange on the driving device

for engagement with the rack to hold the top in place on the holder during movement of the rack in either direction.

3. In combination a spinning toy comprising a holder, a longitudinally movable rack carried by the holder and a centering pin carried by the holder to one side of the rack, a spinning top, a tubular body at one end of the top adapted to receive the centering pin, an attaching flange on the tubular body for attachment to the top, a retaining flange on the tubular body for engagement with the rack to hold the top on the holder and gear teeth between the attaching flange and the retaining flange for meshing engagement with the rack.

WILLIAM LUTHER GANDY.
